UNITED STATES PATENT OFFICE.

GEORGE E. ALLEN, OF PHILADELPHIA, PENNSYLVANIA.

PACKAGE-WINDING MACHINE.

1,135,090.

Specification of Letters Patent. Patented Apr. 13, 1915.

Application filed November 22, 1913. Serial No. 802,381.

To all whom it may concern:

Be it known that I, GEORGE E. ALLEN, a citizen of the United States, residing in the city and county of Philadelphia, State of Pennsylvania, have invented a new and useful Package-Winding Machine, of which the following is a specification.

My invention relates to winding machines, and more particularly to that class of machines which wind yarns or threads into a package through the medium of a suitable core and has for an object to provide a mechanism by means of which the winding operation takes place in such a manner as to produce a wound article or package which is symmetrical in appearance, accurately formed throughout and in which the superposed layers or convolutions of thread are bound together so that there is no opportunity or danger of the package becoming loosened, unwound or disintegrated in any part or parts.

It has for a further object to provide a winding mechanism adapted for use with all grades of yarn or threads so that the softest material may be wound just as accurately and effectively as the harder or coarser yarns.

My invention more particularly comprises a mechanism for guiding to and placing a thread or yarn upon a package so as to conform to and allow for the varying diameter of the usual tapered yarn package as well as the tendency of the package to build up at the ends faster than throughout the body portion thereof. I accomplish this end by employing a combination of elements adapted to cause a variation in the speed of the laying-on mechanism so that the end and body portions of the package are laid not only with a speed proportion to the change in the package diameter, but also with regard to the dead centers of the laying-on mechanism.

In winding packages of tapered form it is evident that one end of the package has a tendency to build up much faster than the opposite end, while the opposite end also has a tendency to build up somewhat faster than the body portion of the package, and therefore it is one object of my invention to compensate the laying-on mechanism so that it moves axially of the package at varying speeds and with a quick return movement at the respective ends of the package.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan of a winding machine embodying my invention; Fig. 2 represents a side elevation of the same; Fig. 3 represents an elevation of the side of the machine opposite from that shown in Fig. 2; Fig. 4 represents a section on line $x-x$ of Fig. 3.

Referring to the drawings, like numerals indicate corresponding parts.

1 designates the main driving shaft of the winding machine, the same being mounted in suitable bearings 2; carried by the base or frame 3. Attention is directed to the fact that the said shaft 1 is provided with suitable bearings at its opposite end or intermediate the ends, but these have not been shown as I have deemed it unnecessary to illustrate the entire length of the shaft. It will be understood, however, that in practice the shaft 1 may be of any length desired, according to the number of forms or packages to be simultaneously wound, but as these winding forms are all similar to the one shown in the drawings as the preferred form, I have for the sake of clearness confined the following description as well as the drawings, to but one of the winding forms and its adjuncts. The shaft 1 is driven from any suitable source of power and carries on the end thereof a beveled pinion 4 meshing with a beveled gear 5 fixed to the counter-shaft 6, this latter being mounted in suitable journals 7. The shaft 6 also has keyed thereto a gear 8 meshing with a similar gear 9, upon the shaft 10, which is preferably arranged parallel to the shaft 6 and mounted in the journals 11. Attention is directed to the substantially elliptical configuration of the gears 8 and 9, since the motion transmitted from the shaft 6 to the shaft 10 is a peculiar

one and bears a definite relation to the thread winding operation. By a closer inspection of the two elliptical gears it will be noted that each has an eccentric relation 5 with respect to its shaft, thus the gear 8 is eccentrically mounted with respect to its long diameter while the gear 9 is similarly arranged with respect to its short diameter, the function of which construction will later 10 appear in the description of the other adjuncts of the mechanism and its operation.

12 designates a disk, plate or like device mounted adjacent one end of the shaft 10 for rotation therewith, and having a crank 15 pin 13 adjustably secured thereto at a suitable point, diametrically opposite to which pin there is a balance weight 14 for the usual purpose in crank driven mechanism.

15 designates a connecting rod secured at 20 one end to the pin 13, and at its opposite end to a wrist pin 16 carried by the reciprocable rod 17 which I prefer to call a traverse rod since it is one element of the laying-on mechanism. The rod 17 is mounted for 25 sliding movement in a guide or guides 18; the outer or intermediate guides necessary are not shown since the outer ends of this rod, as well as its connections, are omitted for the reasons heretofore given in connection 30 with the shaft 1, but it will be understood that the end of the rod 17 is suitably supported and guided in any well known type of guide bearing.

19 designates a thread guide comprising 35 an antifriction eyelet or the like suitably secured to the rod 17 for receiving the thread or yarn 20 from a suitable source such as the reel 21, and delivering the same to the thread laying member 22 which is positioned in alined relation to the thread guide 19 and fixed for rotation upon the shaft 1.

23 designates a fixed rod interposed between 40 the reel 21 and thread guide 19 with which the thread is engaged in order to properly direct it to the surface of the thread laying member 22 as will be apparent.

From the thread laying member 22 the 50 thread passes direct to the package 24 and the latter receives its rotary movement through contact with the aforesaid member 22. In connection with the package 24 attention is directed to the fact that it is 55 movably mounted upon a suitable supporting arm 25, which latter is pivoted at 26 to a suitable part of the base 3 and is held in contact relation with the thread laying member 22 by a weight 27 or the like. In 60 connection with the package mounting any well known type of mechanism may be employed for holding the package in proper position with respect to the thread laying member, the said mounting embodying automatic 65 features if desired for adjusting

the package or moving it into and out of engagement with the member 22, but as this construction forms no part of my present invention, I have therefore shown it as more or less conventionally. The thread laying 70 member 22 in the present instance is provided at one end with an angularly shaped notch or groove 28, each leg of which forms a part of an imaginary helix developed upon the surface of the said member while upon the opposite end of the said thread laying member there is a second angular groove 29, the respective legs of which also form portions of a helix preferably concentric with respect to the helices of the groove 28. It 80 will further be noted that in the preferred form of my invention the two grooves 28 and 29 are arranged at an angle of substantially 90 degrees with respect to each other, that is, the apex of one groove is positioned a quarter turn of the thread laying member from the opposite apex, for a purpose which will later appear.

In the present embodiment of my invention I have shown the thread laying member 90 22 as frusto-conical in shape to form a substantially similar shaped package, but it will be understood that I do not desire to be limited to any definite taper or shape of thread laying member as the same may be 95 varied in contour as desired in order to wind a package of predetermined shape.

In the operation of the device a package form is placed upon its support adjacent the thread laying member 22 and held in 100 contact relation therewith by suitable mechanism, so that upon rotation of the shaft 1 the said form will receive the required rotary movement and also move gradually as the winding increases in thickness. The 105 thread 20 is passed from the reel 21 about the bar 23, then across the face of the member 22 in a plane substantially normal to the axis of rotation of the drum where it is then secured to the package form. Rotation 110 of the shaft 1 causes the member 22 and package form 24 to rotate together at substantially the same surface speed, and simultaneously with this action motion is transmitted through the gearing and crank 115 mechanism to the traverse bar or rod 17, which thereupon commences its reciprocating movement so that the thread passes alternately from one end of the member to the other. This movement causes the thread or yarn to be wound upon the package 24 in the form of superposed helices, and the successive helical windings are built up one upon another with uniform spacing between the strands of each layer, thus giving the 120 wound package a symmetrical appearance as well as a structure incapable of disintegration.

In devices heretofore devised for winding thread and yarn, it has been found that the 130

5 packages are not uniformly wound, either as to shape or to the density of the winding, and the ends of the package will often be built up more than the intermediate portion so that the package breaks down in use or becomes unloosened.

10 I am aware that it has heretofore been proposed to utilize cam grooves for causing a winding mechanism to reciprocate and place a thread upon a form or package, but in practice such grooves soon become worn and the lost motion caused by this wear so changes the relation or timing of the winding parts that the thread is not uniformly placed and the resulting package is 15 unsatisfactory and defective. Furthermore, where the thread itself passes through a cam channel or groove, there is a decided tendency for the sharp edges of the cam to 20 cut or break the thread, and when this occurs and the broken end is replaced in its groove it frequently becomes caught in the surface of the cam and winds directly upon the cam instead of being guided to the 25 package.

In my present construction I have devised a mechanism the parts of which are accurately adjusted and timed with respect to each other and the travel or stroke of the 30 traverse bar 17 has a definite predetermined relation to the length of the package as well as to the longitudinal distance between the reversely arranged slots 28 and 29. Furthermore, it will be noted that the gears 8 and 9 35 are designed with such an eccentricity as to produce substantially a uniform movement to the traverse bar 17 with respect to the body portion of the package, that is, intermediate the ends of the thread laying member 40 which ends are considered as the apices of the grooves 28 and 29. As a matter of fact, however, the action of the two afore- 45 said gears is such as to cause the traverse rod 17 to move toward the smaller end of the package with a slight acceleration while in the opposite direction the reverse is true, this movement of course being in accord with the tapered form of the package. Adjacent each end of the stroke of the traverse 50 bar 17 the gears impart a sudden acceleration to the rod so that it reaches the end of the stroke at a maximum speed and begins its return movement with this speed and then the velocity gradually decreases to the 55 normal velocity for the body of the package and depending, of course, upon the direction of travel.

In connection with the foregoing it will 60 be noted that while the speed of the traverse bar is greater at the larger end of the package than it is along the body of the package to give the required quick return movement, the speed at the smaller end of the package is greater than either the speed for the body 65 portion of the package or for the larger end

of the same, and it will be apparent by reference to the gears 8 and 9 that when the traverse bar is at the end of its stroke adjacent the small end of the package the gear 8 will have its long diameter substantially 70 horizontal and with its longest radius on the side toward the gear 9 while the latter gear will be positioned with its long diameter substantially vertical and the shorter radius of its short diameter on the side toward the 75 gear 8, thus giving the required higher speed for the small end of the package as will be apparent.

Furthermore, in addition to eliminating any chance of the thread piling up at the 80 ends of the package it will be noted that at the moment of changing the direction of movement of the traverse bar the thread will be located in one or the other of the grooves 28 and 29 according to the position 85 of the traverse rod, and consequently the quick return or sudden reversal of direction will not draw upon the thread or exert any stretching action. The function of the two grooves 28 and 29 is therefore an important 90 one since each forms a seat or depressed guide within which the thread rests and is held while the reverse movement takes place, thus forming substantially an auxiliary holder or guiding holder which takes up 95 and distributes what would otherwise be a sudden tension upon the thread. This construction, therefore, makes it perfectly possible to wind the finest, softest and most delicate yarns or threads upon the package 100 without damage, and also it follows that a package may be wound which is either soft or hard according to the texture of the thread used, and I believe this to be an advantage not attained, so far as I am aware, 105 by other package winding machines, since such mechanisms in present day use depend upon maintaining a degree of tension upon the thread not at all practical for the winding of the finer or softer grades of material. 110

As a further point of advantage it may be pointed out that those soft grades of yarn have a tendency to cling or stick together when wound upon a package so that when 115 all grades of goods are wound upon the same tapering package, it is very difficult to unwind the softer yarns without stretching or breaking the threads. By my improved mechanism I am enabled to use packages of different taper so that provision may be 120 made for the softer, finer threads, this being accomplished by employing a package form having a more acute taper so that the clinging action of the threads is overcome and the threads may be readily unwound. 125

The change of speed of the thread placing mechanism and the consequent uniform spacing of the yarn upon the package insures the effective binding of the threads upon the package so that there are no ex- 130

posed points through which loops of the yarn may be thrown out under centrifugal force, which is a tendency which develops more particularly when winding soft yarn.

5 It will now be apparent that I have devised a novel and useful construction of winding machine which embodies the features of advantage enumerated as desirable in the statement of the invention and the 10 above description, and while I have, in the present instance, shown and described a preferred embodiment thereof which has been found in practice to give satisfactory and reliable results, it is to be understood 15 that the same is susceptible of modification in various particulars without departing from the spirit or scope of the invention or sacrificing any of its advantages.

Having thus described my invention, what 20 I claim as new and desire to secure by Letters Patent is:—

1. In a device of the character stated, the combination of a rotatable form, a rotatable thread laying member having surface contact with said form and provided with an angular groove adjacent each end, the portion of said member between said grooves being a smooth uninterrupted surface, a reciprocable thread guide operatively positioned with respect to said rotatable laying member, means to reciprocate said thread guide and means to impart a quick return movement to said thread guide when the thread is within one or the other of said 30 angular grooves.

2. In a device of the character stated, the combination of a rotatable package form or holder, a rotatable thread laying member having surface contact with said form and 40 provided with an angular groove adjacent each end thereof, the apices of said grooves being oppositely disposed with respect to each other, and spaced a distance substantially equal to the length of the package to 45 be wound, while the juxtaposed ends of said grooves are spaced apart to leave an uninterrupted surface there-between, means to reciprocate said reciprocable thread guide, and means timed to impart a quick return 50 movement to said reciprocable thread guide substantially simultaneously with the arrival of the thread at one or the other of said groove apices.

3. In a device of the character stated, the 55 combination of a rotatable package form or holder, a rotatable thread laying member having surface contact with said form and provided with an angular groove adjacent each end thereof, a reciprocable thread

guide operatively positioned with respect to 60 said rotatable laying member, means to reciprocate said reciprocable thread guide, means comprising a pair of substantially elliptical gears in mesh with each other, one of said gears being eccentric to its long 65 diameter and the other of said gears being eccentric to its short diameter for carrying the speed of said reciprocating means as the thread approaches the apex of one or the other of said grooves, and means to drive 70 said gears.

4. In a device of the character stated, the combination of a rotatable package form or holder, a rotatable thread laying member having surface contact with said form and 75 provided with a reciprocable thread guide operatively positioned with respect to said rotatable laying member, means to reciprocate said reciprocable thread guide, means comprising a pair of substantially elliptical 80 gears in mesh with each other for increasing the speed of said reciprocating means at each end of the stroke of said reciprocable thread guide, one of said gears being eccentrically mounted with respect to its long 85 diameter and the other of said gears being eccentrically mounted with respect to its short diameter, whereby the acceleration of 90 said reciprocable thread guide is greater at one end of its stroke than at the other. 90

5. In a device of the character stated, the combination of a rotatable package holder, a rotatable thread laying member adjacent thereto having an angular groove adjacent each end thereof, while the intermediate 95 length of the surface of said member is uninterrupted, the respective sides of each groove forming a portion of a helix developed about said laying member, the apices of said grooves being operatively disposed with respect to each other and located out of axial alinement, a reciprocable thread guide operatively positioned with respect to said rotatable laying member, means to reciprocate said reciprocable thread 100 guide, and means timed to impart a quick return movement to said reciprocable thread guide when the thread is within one or the other of said angular grooves. 105

In testimony that I claim the foregoing 110 as my invention, I have hereunto signed my name this twentieth day of November, A. D. 1913.

GEORGE E. ALLEN.

In the presence of—

JOHN LINTON,
WILLIAM J. GLENN.
